UNITED STATES PATENT OFFICE.

JAMES BARKER, OF PHILADELPHIA, PENNSYLVANIA.

DESIGN FOR A SIDE FRAME FOR DENTIST AND BARBER CHAIRS.

No. 38,620.

Specification for Design.

Patented June 11, 1907.

Application filed April 29, 1907. Serial No. 371,024. Term of patent 14 years.

To all whom it may concern:

Be it known that I, JAMES BARKER, a citizen of the United States, residing in Philadelphia, Pennsylvania, have invented a certain new, original, and ornamental Design for Side Frames for Dentist and Barber Chairs, of which the following is a specification, reference being had to the accompanying drawing, forming part thereof, which represents a side view of the side frame.

I claim:—

The ornamental design for a side frame for dentist and barber chairs, as shown.

JAMES BARKER.

Witnesses:

Jos. H. KLEIN,
